SEWING MACHINE

Waldemar A. Ayres, Lakewood, Ohio, assignor to White Sewing Machine Corporation, Lakewood, Ohio, a corporation of Delaware

Application December 27, 1954, Serial No. 477,782

9 Claims. (Cl. 112—221)

This invention relates to a sewing machine and more particularly to an improved drive mechanism for the needle bar of a sewing machine.

When sewing machines have been operated at high speeds excessive vibrations have been present and this draw-back has resulted in limiting successful high speed operation of sewing machines.

A large contributing factor to the creation of vibrations during high speed operation of sewing machines has been the arrangements utilized for actuating the reciprocating needle bar. The necessity of rapidly changing the direction of movement of the mass of the reciprocating needle bar contributes largely to the creation of vibrations in the sewing machine head during high speed operation. Also the mechanisms heretofore used for translating rotary motion into reciprocating motion of the needle bar have been inducive to the creation of vibrations at high speed operation.

An object of the invention is to provide in a sewing machine a needle bar construction and a mechanism for reciprocating the same which is of such character that the creation of vibrations will be held to a minimum and the mechanism will permit high speed operation of the machine substantially without vibration.

Another object of the invention is to provide in a sewing machine an improved mechanism for reciprocating the needle bar and which includes means for counterbalancing the reciprocating needle bar so as to substantially eliminate vibrations even at high speed operation and which mechanism is quiet in operation both at high and low speeds.

A further object of the invention is to provide in a sewing machine an improved mechanism for reciprocating the needle bar at high speeds and substantially without vibration and which mechanism is so constructed as to readily lend itself to the inclusion therein as a part thereof of a rotary take-up for the upper or needle thread of the sewing machine.

A further object of the invention is to provide an improved needle bar supporting unit which mounts therein the actuating mechanism for the needle bar and the rotary take-up for the upper or needle thread and which unit with the parts referred to therein can as a unit be secured in and removed from the free end of the horizontal arm of the sewing machine head, thus facilitating the assembly of the sewing machine.

Further and additional objects and advantages not hereinbefore specifically referred to will become apparent hereinafter during the detailed description of an embodiment of the invention which is to follow and which embodiment of the invention is illustrated in the accompanying drawings forming a part of this specification and wherein,

Fig. 1 is a vertical sectional view through the sewing machine head and the bed plate thereof and is taken substantially on line 1—1 of Fig. 2 but with a portion of the endless belt shown in elevation and illustrates the unit supporting the reciprocating needle bar and the

2

actuating mechanism for the needle bar as well as the take-up for the upper or needle thread.

Fig. 2 is a top plan view of the sewing machine head shown in Fig. 1.

5 Fig. 3 is a fragmentary horizontal sectional view taken substantially on irregular line 3—3 of Fig. 1 looking in the direction of the arrows.

Fig. 4 is a bottom plan view of the take-up for the upper thread and is taken from line 4—4 of Fig. 1.

10 Fig. 5 is an exploded sectional and partial elevational view of the parts of the wobble actuating mechanism for the reciprocating needle bar.

Fig. 6 is a detail elevational view of an element of the wobble actuating mechanism for the reciprocating needle bar.

Fig. 7 is a detail elevational view of another element of the wobble actuating mechanism for the reciprocating needle bar.

20 Fig. 8 is a detail end view of the element shown in Fig. 7 and is taken looking from the right hand side of Fig. 7.

Fig. 9 is a detached elevational view of the reciprocating needle bar.

25 Fig. 10 is a detached elevational view of the reciprocating needle bar turned 90° from the position of the needle bar in Fig. 9.

Fig. 11 is a detached elevational view of the needle bar counterbalancing plunger, and

30 Fig. 12 is a detached elevational view of the needle bar counterbalancing plunger shown in Fig. 11 but with the plunger turned 90° from the position of Fig. 11.

Referring first to Figs. 1 and 2, the sewing machine head embodying the invention comprises the bed plate 15 beneath which is mounted the sewing mechanism as will be well understood. The bed plate 15 of the sewing machine head has on its upper side either integral therewith or secured thereto a gooseneck consisting of a hollow vertically extending standard 16 which connects at its upper end with an integrally formed hollow horizontal arm 17 which overlies the bed plate 15. The horizontal arm 17 is provided interiorly with a partition or end wall 18, the upper end 18a of which is offset toward the standard 16, that is, offset toward the right as viewed in Fig. 1.

The outer or free end of the horizontal arm 17 has secured to the wall 18 the supporting unit carrying the needle bar and its actuating mechanism. The unit is enclosed by a housing 19 the top or upper side of which is provided with an opening 21. The housing 19 forms a continuation of the horizontal arm 17 and is secured thereto by screws 20.

55 A supporting unit for the needle bar, the counterbalancing plunger and the actuating or driving mechanism for the needle bar and plunger is mounted on the outer end of the horizontal arm 17 and is secured to the partition or wall 18. This unit comprises an attaching portion 22 which is secured to the partition 18 by suitable securing means such as screws or bolts and extends vertically of the partition from its lower end to the point thereof where the offset upper end 18a commences, see Figs. 1, 2 and 3. The portion 22 has integral outwardly extending vertically spaced upper and lower horizontal walls 23 and 24. The arms 23 and 24 at their outer ends are integral with the vertically extending portion 25 of the unit which mounts the needle bar, the counter balancing plunger and the usual presser foot rod as will later be explained.

70 The walls 23 and 24 are provided with vertically aligned openings in which are mounted suitable bearing bushings 26 which rotatably support a vertically extending drive shaft 27 forming part of the drive for the reciprocating needle bar and counterbalancing plunger. The shaft 27

extends upwardly above the wall 23 and into the opening 21 of the housing 19.

A circular block 28 provided with a central bore 29 is pinned or keyed to the shaft 27 and has its horizontal upper end 30 engaging the flange on the lower end of the upper bushing 26 while the opposite or lower end of the block is inclined to the axis of the shaft 27 as indicated at 31, the angle of inclination being shown as substantially 45°. A spacer ring 32 provided with similarly inclined upper and lower ends is mounted on the shaft 27 with its upper inclined end engaging the lower inclined end 31 of the block 28. The ring 32 mounts on its circumference the inner race 33 of an antifriction bearing, the outer race of which is indicated at 34 and the balls at 35, see Figs. 1 and 5.

The outer or actuating ring 36 is mounted on the circumference of the outer race 34 and this ring 36 is operatively connected to the reciprocating needle bar as will later be explained. A block 37, identical with the block 28, is keyed to the shaft 27 but in inverted relationship to the block 28 so that its inclined upper end that is complementary to the inclined lower end 31 of the block 28 bears against the ring 32, the inner and outer races of the bearing and the outer or actuating ring 36.

A similar actuating mechanism to that just described is mounted on the shaft 27 adjacent the wall 24 and the parts of this mechanism are identified by the same reference numerals as used for the first mentioned mechanism but with the exponent *a*.

The two mechanisms just referred to will be designated herein as wobble actuating mechanisms, with the upper one being the actuating mechanism for the reciprocating needle bar and the lower one the actuating mechanism for the reciprocating counterbalancing plunger. It will be noted that the lower block 37a of the actuating mechanism for the plunger engages the flanged upper end of the lower bushing 26 and that said upper and lower actuating mechanisms are mounted on the shaft 27 so as to be 180° out of phase.

The shaft 27 above the wall 23 has fixed to it a drive pulley 38 and above the drive pulley 38 there is fixed to the shaft 27 within the opening 21 of the top of the housing 19 a circular disk 39 forming a hand wheel.

The housing 19 is open at its lower end and the shaft 27 extends below the wall 24 and has fixed to it a disk 40 forming part of a thread take-up for the needle thread (see Figs. 1 and 4). The disk 40 radially outwardly from its center has a headed screw or post 40a threadedly connected to it and located in an elongated slot 41a of a lever arm 41. The lever arm 41 is pivoted at one end to a block 41b secured to the wall 24 while the opposite end of the lever arm is provided with an opening 41c through which passes the needle thread.

The vertically extending portion 25 of the supporting unit is provided with a pair of parallel vertically extending bores 42 and 43 which are aligned in the longitudinal direction of the horizontal arm 17. Also the portion 25 is provided with a slot 44 which starts at the wall 24 and passes transversely through the bores 42 and 43 to the outer or left hand end of the portion 25. The slot 44 extends vertically from the upper end of the portion 25 downwardly to the lower side of the wall 24 for a reason which will later be apparent.

Slidably mounted in the bore 42 is the reciprocating counterbalancing plunger 45, the upper end of which is bifurcated to provide spaced parallel ears 46 and which ears are provided with aligned openings 47. The bore 43 has mounted therein adjacent its lower end a bushing 48 and spaced vertically above the bushing 48 a second bushing 49. The bushings 48 and 49 are provided with aligned bores which slidably mount and guide the reduced tubular portion 50 of the reciprocating needle bar.

The reciprocating needle bar at the upper end of the reduced tubular portion 50 is provided with an enlarged cylindrical portion 51 which has a sliding fit in the bore

43. It will be seen that the reciprocating needle bar is adequately guided for true vertical reciprocation by the spaced bushings 48 and 49 and by the sliding fit of the enlarged upper end 51 of the needle bar in the bore 43.

The enlarged upper end 51 of the needle bar is bifurcated to provide a pair of upwardly extending spaced parallel ears 52 and said ears 52 are provided with horizontal aligned openings 53. A rocker shoe 54 is rockably mounted between the ears 52 on a pivot pin 55. The lower end of the rocker shoe 54 is provided with an opening 56 which slidably receives the free end of an actuating pin 57, the opposite end of which is connected to the actuating ring 36 as, for instance, by the threaded connection illustrated. A similar shoe 54a is pivotally mounted between the ears 46 of the counterbalancing plunger 45 but is inverted relative to the shoe 54 so that the opening 56a of the shoe 54a is located at the upper end of the shoe. The opening 56a of the shoe 54a slidably receives the free end of an actuating pin 57a, the opposite end of which is operatively connected to the actuating ring 36a of the lower wobble actuating mechanism.

It will be recalled that the upper or needle bar wobble actuating mechanism and the lower or counterbalancing plunger wobble actuating mechanism are disposed 180° out of phase, wherefore when the shaft 27 rotates the pins 57 and 57a will cause oppositely phased reciprocation of the needle bar and of the counterbalancing plunger at the same speeds.

It will be noted that the slot 44 in the portion 25 of the supporting unit accommodates the oscillating movement of the pins 57 and 57a and the rocking movements of the shoes 54 and 54a. It will also be noted that when the pin 57 is in its lowermost position and the pin 57a is in its uppermost position as indicated by dash and dot lines in Fig. 1 there will be no interference between these parts or between the rocking shoes 54 and 54a.

As already stated, the needle bar is hollow or tubular and hence the mass of the needle bar can be correlated to the mass of the counterbalancing plunger 45, even though the latter is substantially shorter in length than the needle bar, it being noted that the plunger 45 is of solid cross section and substantially greater in diameter than the diameter of the needle bar.

The mass of the needle bar and the needle clamping mechanism 58 at the lower end of the needle bar and of the needle 59 clamped in said mechanism 58 can be equal to the mass of the plunger 45, wherefore the oppositely phased reciprocation of the needle bar and plunger will be fully counterbalanced, thereby eliminating vibrations particularly at high speeds. Also the oppositely phased upper and lower wobble actuating mechanism on the shaft 27 being identical counterbalance each other and reduce to a minimum any vibration which might occur during their operation.

The portion 25 of the supporting unit is provided with a third vertically extending bore located behind and parallel to the bore 43 and slidably mounting the usual presser foot rod 60, on the lower end of which is mounted the usual presser foot 61.

An endless belt 62 extends around the pulley 38 and is connected to a drive source, not shown, and which source also is operatively connected to a sewing mechanism, not shown, and located below the bed, it being understood that said source and connections cause the parts to be operated so that the needle bar will reciprocate in proper timed relationship to the sewing mechanism as is well understood in the art.

When the belt 62 rotates the shaft 27 during the operation of the sewing machine the needle bar 50 and the counterbalancing plunger 45 will reciprocate in oppositely phased relationship. Also at this time the disk 40 fixed to the lower end of the shaft 27 will rotate and the headed screw or post 40a acting in the slot 41a of the lever arm 41 will oscillate the latter in timed relationship to the

reciprocation of the needle bar. It will be understood that as the needle bar moves in its upward stroke the lever arm 41 will move in a direction such as to take up the slack in the needle thread which passes through the opening 41c in the arm 41 and through the eye of the needle. It will also be understood that when the needle moves in its downward stroke the lever arm 41 will move in a direction to slack off the needle thread and provide sufficient thread for the sewing operation. In addition, it will be understood that the needle thread passes from a suitable supply spool or bobbin mounted on the sewing machine head through a tensioning device, not shown, and through thread guiding elements from the spool or bobbin through the eye or opening 41c to the eye of the needle as will be well understood in the art.

From the foregoing detailed description of an embodiment of the invention it will be evident that an improved drive for the reciprocating needle bar has been provided and which drive enables quiet vibrationless high speed operation of the sewing machine and particularly of the reciprocation of the needle bar. In addition, it will be noted that improved and efficient take-up for the upper or needle thread is provided and that said take-up can be incorporated readily into the actuating mechanism for the needle bar and the counterbalancing plunger.

Although a preferred embodiment of the invention has been illustrated and described herein it will be understood that the invention is susceptible of various modifications and adaptations within the scope of the appended claims.

Having thus described my invention, I claim:

1. In a sewing machine, a head including a hollow vertical standard and a hollow horizontal arm projecting from said standard and mounting adjacent its outer end a vertically reciprocating needle bar and provided in its upper wall adjacent to its outer end with an opening, a vertically extending rotatable shaft in said arm adjacent and parallel to said needle bar and coaxial with said opening and extending into the same, means operatively connecting said shaft with said needle bar to effect reciprocation of the latter upon rotation of said shaft, a hand wheel disk fixed to the upper end of said shaft in said opening, thread take-up means operatively connected to the lower end of said shaft, and means for rotating said shaft to actuate said thread take-up and to reciprocate said needle bar.

2. In a sewing machine as defined in claim 1 and wherein in said thread take-up means includes a disk fixed to the lower end of said shaft and provided on its lower side with a downwardly extending headed post spaced radially outwardly from the axis of said shaft, a lever arm pivoted at one end to a fixed part of the head and provided at its other end with an opening through which the needle thread is adapted to pass and having intermediate its ends an elongated slot in which said headed post is located.

3. In a sewing machine as defined in claim 1 and wherein in the means operatively connecting said shaft with said needle bar to effect reciprocation of the latter upon rotation of said shaft includes a pair of block members secured to said shaft in axially spaced relationship and having their adjacent ends inclined to the axis of said shaft, a spacer ring of less diameter than said members on said shaft intermediate said members and having its opposite ends complementary to and contacting the inclined ends of said members, an antifriction bearing surrounding said ring with its inner race mounted on the circumference of said ring, an actuated ring mounted on the outer race of said bearing, and an operative connection between said actuated ring and said needle bar.

4. In a sewing machine, a head including a hollow vertical standard and a hollow horizontal arm projecting from said standard and mounting adjacent its outer or

free end a vertically reciprocating needle bar and provided in its upper wall adjacent to its outer or free end with an opening, a vertically extending rotatable shaft in said arm adjacent and parallel to said needle bar and coaxial with said opening and extending into the same, a hand wheel disk fixed to the upper end of said shaft in said opening, thread take-up means operatively connected to the lower end of said shaft and located below the bottom wall of said horizontal arm, a vertically reciprocating counterbalancing plunger parallel to said needle bar and said shaft and located intermediate the same and having a mass which substantially equals the mass of the needle bar, a pair of axially spaced oppositely phased wobble actuating mechanisms on and rotatable with said shaft, an operative connection between one of said mechanisms and said needle bar and an operative connection between the other of said mechanisms and said plunger for translating rotation of said mechanisms into oppositely phased reciprocation of said needle bar and plunger, and means for rotating said shaft to actuate said thread take-up and to reciprocate said needle bar and said plunger.

5. In a sewing machine, a head including a hollow vertical standard and a hollow horizontal arm projecting from said standard, a supporting unit secured to the free end of said horizontal arm, a vertically extending shaft rotatably supported in said unit in vertically spaced bearings, a hand wheel fixed to the upper end of said shaft above the upper of said bearings, a needle bar supported by said unit for vertical reciprocation and parallel to said shaft, means operatively connecting said shaft with said needle bar to effect reciprocation of the latter upon rotation of said shaft, and means for rotating said shaft.

25 6. In a sewing machine as defined in claim 5 and wherein a counterbalancing plunger parallel to said needle bar and shaft and intermediate the same is supported by said unit for vertical reciprocation, and means is provided for operatively connecting said shaft with said plunger to effect reciprocation of the latter upon rotation of said shaft in opposite phase to the reciprocation of the needle bar.

30 7. In a sewing machine as defined in claim 6 and wherein said shaft below the lower of said bearings has operatively connected to it a thread take-up means.

35 8. In a sewing machine as defined in claim 6 and wherein a pulley is fixed to said shaft intermediate the upper of said bearings and said hand wheel, and a shaft rotating belt extends around said pulley.

40 9. In a sewing machine as defined in claim 6 and wherein the means operatively connecting said shaft with said needle bar includes a pair of block members secured to said shaft in axially spaced relationship intermediate said bearings and having their adjacent ends inclined to the horizontal, a spacer ring of less diameter than said members on said shaft intermediate said members and having its opposite ends complementary to and contacting the inclined ends of said members, an anti-friction bearing on said ring with the inner race thereof carried by the circumference of said ring, an actuating ring on the outer race of said bearing, and an operative connection between said actuating ring and said needle bar.
